UNITED STATES PATENT OFFICE

GEORGE E. DOREY, OF EVANSTON, ILLINOIS, ASSIGNOR TO ENTERPRISE RAILWAY EQUIPMENT COMPANY, OF CHICAGO, ILLINOIS, A CORPORATION OF ILLINOIS

DUMP CAR CONSTRUCTION

Application filed August 23, 1930. Serial No. 477,270.

My invention relates to improvements in dump car construction.

An object of my invention is to provide a discharge door and co-operating means on the door and car structure for obtaining tightly closed doors.

Another object of my invention is to provide a discharge door having a simple door latching mechanism carried thereby, whereby the door may be manually swung to a nearly closed position and automatically retained in such position.

Still another object of my invention is the provision of a door latching device which will operate to exert a lifting and a wedging action on a discharge door to move the same from a nearly closed to a fully closed position by operation of said device.

Still another object of my invention is to provide a cast metal door having integral portions formed therein co-operating with integral ribs and reinforcements to accommodate latching means whereby the number of door and door latching parts may be reduced.

Another particular object of the invention is to provide a latching device incorporating a bodily movable shaft having projecting portions adapted to co-operate with shouldered means on the car structure, and being so mounted as to be moved by rotation thereof, my object being further to provide means for controlling the movement of the shaft to increase the leverage towards the end of the latching operation.

My invention further resides in certain other features of construction and detail of parts such as will be more fully pointed out hereinafter and claimed.

For further comprehension of my invention, reference may be had to the accompanying drawings, wherein,—

Figure 1 is a vertical transverse sectional view taken through the lower portion of a hopper car and showing slightly more than one-half the width thereof;

Fig. 2 is a longitudinal vertical side sectional view on line 2—2 of Fig. 1;

Fig. 3 is a longitudinal vertical elevation of that part of the structure illustrated in Fig. 1;

Fig. 4 is a longitudinal vertical elevational view similar to Fig. 3 with the door latching shaft in section, said view illustrating the door in a nearly closed position;

Fig. 5 is a longitudinal vertical elevational view similar to Fig. 3, said view illustrating the door in a partly closed position with the latching shaft in retaining engagement with an auxiliary shoulder on the door retaining bracket;

Fig. 6 is an enlarged detail view of the outer end of the outer shouldered latching member;

Fig. 7 is an enlarged detail view of the inner shouldered member as viewed in Fig. 6;

Fig. 8 is a view illustrating a modified form of door; and

Fig. 9 is a side elevation of the door illustrated in Fig. 8 as viewed from right to left.

Referring first to the construction illustrated in Figs. 1 to 7 inclusive, wherein my improvements are shown as applied to a car of the so-called W-hopper type having a door hinged adjacent its upper portion and mounted for vertical swinging movement:

In said drawings, 10 denotes one of the side walls of the car, 11 the lower chord of the car side, 12 one of the beam sections employed to make up the girder center sill of well known form. The center sill structure is built up by the employment of two of these center sill sections united by a top cover plate 13 and having a surmounting ridge 14 of A-shape. As customary in the W-type of car, a transversely extending ridge is formed by the ridge sheet 15 which constitutes the upper wall of a hopper, it being understood there are a plurality of hoppers in the car, two on each side of the center sill and arranged in pairs transversely of the car. Inasmuch as the construction is the same for each hopper, the description herein will be confined to only one of such hoppers:

Each of said hoppers is defined by a longitudinally sloping hopper sheet 16, a vertical inner side hopper sheet 17, and an outside hopper sheet 18, the latter sloping inwardly towards the longitudinal center line of the car and having its margin 19 bent outwardly as shown, and then substantially in the gen-

eral direction of the main plate as indicated at 20, to present a Z-shape section, said bend 19 providing an abutment for the door. The inner side hopper sheet 17 is secured to the 6 side of the center sill and deflected at an angle beyond the outstanding marginal flange 112 of the center sill and thence downwardly to provide a substantially vertical depending portion 21 having its margin formed with an 10 inwardly directed sloping portion 22, said portion 22 being flanged outwardly at 23, and thence in the general direction of the plate, as at 24. The portion 23 thus provides an abutment for the door, and the portion 24 a shoulder adjacent the abutment.

The outer edge of the bottom sloping hopper 16 is rigidified by a member A which is 20 preferably formed of cast metal and includes a main portion extending along the edge of the sheet as indicated at 25, Fig. 7, and an upwardly extending portion at each end indicated at 26 and 27 respectively. These upwardly extending portions overlie the inner and outer hopper sheets respectively and are 25 secured thereto. The member A is preferably formed with an outstanding portion 28 of heavier section than the main portion and constitutes an abutment for the door, said abutment being in substantially the same line 30 as and forming a continuation of the abutments on the respective inner and outer side hopper sheets, thus forming a substantially continuous abutting surface for the three unsupported door edges. The member A adjacent the abutment 28 is formed with a heavy 35 depending portion of bulb-like formation 29, forming a shoulder adjacent to the ledge 28. The member A adjacent the body portion 25 is formed with an integral depending flange 40 disposed substantially normal to the plane 30 of the sloping floor and acting as a reinforcement for the same.

Adjacent the edge of the upper sloping floor formed by the ridge sheets, the sheet is 45 reinforced by a member B preferably formed of cast metal with angularly related flanges, one of said flanges 31 being secured to the sheet and the other of said flanges 32 outstanding therefrom. The member B is provided with a wall portion 33 at its inner end, which is attached to the center sill, and at its outer end said member is provided with an integral flange portion 34 disposed in overlying relation to the outer side hopper sheet 55 18. The outer hopper sheet 18 is rigidified by an additional plate member C which extends contiguously with the marginal abutment 19 of the plate, and is sandwiched between the hopper sheet and the respective 60 overlying flanges 27 and 34 of said members A and B. Outstanding from the depending flange 32 of the member B are two hinge lugs 35 each adapted to receive a hinge pin 36 whereby a discharge door D is pivotally 65 mounted in position.

The discharge door D is preferably formed of cast metal with outwardly extending flanges at its margin, so as to provide a top horizontally extending flange 37 preferably of arcuate formation, inner and outer side 70 flanges 38, and a lower flange 39 adjacent the free edge of the door, said respective flanges 37, 38 and 39 co-operating to form a continuous reinforcement around the edge of the door. Extending across the door, between 75 and integrally uniting said inner and outer side flanges 38, are a pair of depending reinforcing flanges 40 and 41 respectively disposed adjacent the hinge edge of the door and the outer edge thereof, but spaced an appreciable distance from said edges.

Integrally connecting said respective flanges 40 and 41 are a plurality of integral flanges indicated at 42, 43, and 44. Substantially in alignment with the central rib 43 80 are ribs 45 adapted to continue the plane of the rib 43 to the respective inner and outer edges of the door. The door D is pivotally mounted by integral lugs 46 to the respective hinge bracket portions 35. Extending 90 between the outer flange 39 and the flange 41 are a plurality of pairs of integrally formed spaced lugs 47 adapted to co-operate with a portion of the latching mechanism in a manner as will be fully pointed out here- 95 inafter.

The door latching mechanism broadly includes a bodily movable shaft 48 loosely mounted to have bodily movement along the outer face of the door, and spaced appreciably from the main body of the door to clear the side flanges and other integral door bracing. The inner and outer side flanges 38 are provided with transversely widened portions 49 and 50 respectively, which extend through- 100 out the extent of movement of the shaft and constitute abutment runways for the shaft. The shaft 48 projects beyond the respective ends of the doors and beyond the inner and outer side walls 17 and 18 and cooperates 110 with inner and outer shouldered brackets F and G, respectively mounted on the inner and outer hopper sheets.

Rigidly mounted on the shaft and in alignment with spaced lugs 47 on the door are hub 115 members 51, each including a sleeve portion 52 rigidly united with the shaft by means of rivets 53. Each hub member 51 includes a pair of spaced arms 54 disposed in alignment with the lugs 47 on the door, the space be- 120 tween said arms 54 being substantially equal to that between the pair of lugs 47, and interposed between said arms 54 on the hub and lugs 47 on the door is a link member 55. The link is pivoted at one end to the hub by a 125 pivot 56 disposed at an appreciable distance from the axis of the shaft, and the opposite end of the link is pivoted between the lugs 47 and by a pivot 57.

Disposed outwardly of the shaft adjacent 130

the respective side edges of the door are strap members 58 and 59, which form guides to prevent outward movement of the shaft, and which co-operate with the abutments 49 and 50 to confine the path of movement of the shaft substantially parallel with the plane of the door. The guide 58 is formed with a bent portion secured at its lower end to the depending flange 41 by a rivet 60. Adjacent the upper limit of travel of the shaft said guide is bent inwardly to present a wall portion 61 riveted at 62 to the outer face of the door plate. The outer guide member 59 is attached to the rib 41 in a similar manner and is extended upwardly beyond the limit of movement of the shaft and fastened to the main body of the door by a rivet 63, guide 59 is spaced from the door by a boss 64 formed integrally with the door and outstanding therefrom, said boss member having a portion adapted to present a supporting pivot for a swingingly mounted cam 66. The cam is adapted to be swung in the path of movement of the shaft to retain the latter in latching position.

Rearwardly of the cam, the boss 64 is formed with a portion 67 of enlarged diameter adapted to present a wall 68 adapted to limit inward movement of said cam. The boss 64 being in the path of the rib 42 is virtually an enlargement of the latter. The cam 66 is formed with a projecting lug portion 69 constituting a pry-off portion, and on the opposite side thereof is formed with a stop lug 70 adapted to contact with the side flange of the door to limit the throw of the cam.

The shaft 48 is preferably formed adjacent its outer end with a yoke comprising a pair of spaced jaws 71 adapted to receive therebetween a suitable bar or operating tool for the purpose of actuating the shaft by rotation thereof.

The shouldered brackets F and G which engage with the projecting portions of the shaft are disposed in overlying relation with the respective upturned portions 26 and 27 of the lower marginal reinforcing and sealing member A, and also extended upwardly above the same to permit attachment to the side hopper sheets independently of the member A. Each of said brackets includes a main locking shoulder 72, Figs. 6 and 7, with which the projecting portion of the shaft is adapted to co-operate when in its normal locking position, it being understood that the shaft is so disposed on the door as to gravitate to its normal locking position due to its own weight. In order to lift said shaft a sufficient distance to allow the same to drop into engaging position behind the shoulders 72, each bracket is provided with inclined portions 73 which constitute a bevelled approach to said shoulders, said bevelled portions being adapted to engage beneath and lift the

shaft as the door is slammed towards closed position.

The relation of the shaft and associated pivotal points between the shaft and the link 55 and between the link 55 with the door is such as to provide for rolling movement of the shaft along the faces of the outer abutment walls during initial displacement of the shaft from its normally latched position, thus providing for ready upward displacement of the shaft as it engages with the beveled portions of the brackets. With the latching device in the normally latched position, the intermediate portion of the link 55 rests against the shaft acting to limit further turning movement of the shaft, said intermediate portion of the link being concaved as indicated at 155 to accommodate the shaft. It will be noted that as the shaft moves downwardly towards the final locked position the axis of the shaft gradually approaches a center line passing through the respective pivots 56 and 57, thereby effecting a toggle leverage for forcing the shaft to final latched position. However, due to the fact that the axis of the shaft is not permitted to pass said center line to complete a toggle with respect to pivots 56 and 57, the shaft is in a position which admits of ready displacement when a lifting force is exerted thereon.

The outer shouldered bracket G is provided with an auxiliary shoulder 74, Fig. 6, disposed slightly beyond the main shoulder 72 and connected therewith by an inclined wall 75, said shoulder 74 being of a character to engage the shaft and hold the door in a nearly closed position as the door is urged towards closed position, as shown in Fig. 4. It will be appreciated that in swinging the door towards closing position the operator would normally apply force at a point adjacent the outer edge corner of the door with the result that the inner edge of the door will lag due to the fact that the unsupported weight of the door at the end remote from the point of application of the force causes the door to spring slightly. Hence, in order to provide for this condition, the inner shouldered bracket F if formed with an inclined wall section 76 connecting the bevelled approach and the main shoulder, whereby the shaft may coact with said inclined wall section as indicated by dotted lines at 77 in Fig. 7, and hence, when the shaft is rotated in a closing direction, it will cause a lifting movement to be exerted on the door to raise the inner lagging end of the door towards closed position. The outer end of the door in the meanwhile is retained in its nearly closed position by reason of the holding action of auxiliary ledge 74, the relative position between the shaft and shoulders being indicated in Figs. 6 and 7, wherein the shaft is indicated in

partly closed position at 78 and fully closed at 79.

Intermediate the bracket F and the overlying wall 30 the reinforcing plate member 5 C is formed with an outwardly flared portion 80 adapted to act as a reinforcement for the plate and also as a protection for the outwardly formed abutting portion 19 on the said wall. Said plate may also be flanged at 10 its opposite edge as indicated at 81 for reinforcement purposes. In hopper cars of this character there is a tendency for the load to pack and freeze during severe weather conditions, which fact results in the outer side 15 plate being hammered to free the load, and it has been a common practice to incorporate a striking plate and door marginal abutment in a unitary member, a construction which renders the door and marginal abutment 20 liable to distortion, tending to cause leakage. My improved construction decreases the liability by mounting the striking and reinforcing plate C in close proximity to but independently of the door abutment and providing the outstanding flange 80 in protecting 25 relation to said abutment.

The arrangement of the hopper construction with the side walls flanged to provide 30 abutments for the doors and tied at the top and bottom with sturdy members extending from side to side of the hopper, in combination with the heavy flanged cast metal door, and powerfully acting wedging means to force the door in tight engagement with the 35 hopper abutments all around the door, provide for a construction secure against leakage. In the mechanism shown in Figs. 8 and 9 my improvements are shown as applied to a door structure having upwardly 40 turned flanges. In this construction the door has a shaft L loosely mounted thereon and having end portions projecting beyond the sides of the door for co-operation with retaining means on the car, said shaft having 45 a pair of crank members M fixedly united therewith. Connecting the shaft and door are the two link members N, and pivotally mounted on the door to restrain movement of the shaft is a cam member P. The door 50 proper includes a body portion 200 having upturned integral reinforcing marginal flanges indicated at 201, 202 and 203 respectively. The door on its under side is reinforced by a series of integral ribs 204, 205 55 and 206 extending across the door from side edge to side edge. Extending transversely of said last named ribs are other ribs 207, 208, 209, 210 and 211. Adjacent each side edge of the door there are provided integral 60 portions 212 and 213 constituting runways for the shaft L, and on the outer sides of said runways are overlying wall members 214 and 215 respectively adapted to form outer guides to prevent outward movement of the shaft. 65 A portion of the wall 214 is cut away in

Fig. 8 to reveal the wall 212. Mounted between wall 215 and a boss 216 on the door is the cam member P. The integral portion 213 and wall 215 are united by a web 217 which limits movement of the cam P to the position indicated by dotted lines in Fig. 8. The upper end of each link member is extended between a pair of arms 218 formed on the crank member M and pivotally mounted therein by a pivot 219. The lower opposite end of the link is extended between a pair of walls formed by the lugs 220 integral with the door, and pivotally united to said walls by a pivot 221.

The outer end of the shaft is formed with 60 a pair of spaced projections 222 forming a yoke to accommodate a removable operating bar therebetween. The door adjacent its upper portion is formed with a plurality of integral hinge lugs 223, whereby the door is 65 pivotally supported on the car.

I claim:—

1. In a railway car, the combination of a door movably mounted and adapted to be latched in fixed relation to a retaining bracket mounted independently of the door, said bracket having a shoulder and a beveled approach leading thereto, a bodily movable latch member adapted to assume a normally locked position and having a projecting portion adapted to engage with the beveled approach of the bracket to displace said latch from its normally locked position, said latch member being adapted to be moved by rotation thereof, inner and outer guide walls between which said latch member is mounted, and means for controlling movement of the latch member on rotation thereof, said means including a link pivoted to the latching member and to means disposed in fixed relation to the door, the pivotal points of said link being disposed in such relation to the guides and latch member as to provide substantially for a rolling contact between the latching member and the said guide walls during initial displacement of the latch member from its normally latched position.

2. In a railway car, the combination of the car body and a dumping door, shouldered means carried by the body of the car adjacent each side edge of the door, movably mounted means carried by the door and having projecting portions adapted to engage with the shouldered means at the respective side edges of the doors, a link member connecting said means with the door, said door embodying in an integral unit, hinge brackets for pivotally supporting the door on the car body, abutments for the latching members, and lugs adapted to receive one end of the link.

3. In a railway car, having a hopper section including side walls, the combination of a dumping door hinged adjacent its upper margin and movable to a closed position into 130

engagement with the side walls; shouldered locking brackets carried by the respective side walls, a latching member carried by the door and having projecting portions extending beyond the edges of the door for cooperating engagement with the shouldered brackets, guides within which the latching member is adapted to move, a rigid arm member outstanding from the latching member, a link pivoted to said arm and to the door, said latching member being mounted to gravitate to normal latching position, means associated with the shouldered brackets for causing automatic engagement between the latching member and the shouldered members as the door is moved to closed position.

4. In a railway car door of the type having a latching member movably mounted on the door and movable therewith and being united with the door by link means, the combination of a door embodying a main body section and integral reinforcing rib means extending from side to side of the door, supplementary rib means extending between and integrally united with said first named rib means, integral abutment means for the latching member, and integral receiving means for one end of the link.

5. In a railway car, an integral door unit comprising a body section, a plurality of reinforcing rib means extending from side to side of the door, supplementary rib means extending at an angle to and connecting said main ribs, abutment means for a movable door latching device, and bracket means presenting a retaining means for one end of a connection between the door and latching means.

6. A railway car door adapted to be pivotally mounted and having a main body section and hinge lugs formed integrally therewith adjacent one end of the body section, said door being reinforced by integral depending ribs extending in the general direction of the hinge axis and disposed adjacent the hinge and outer edges of the door, other integral ribs extending at an angle to and between said first named ribs, door latching means movably mounted between said first named ribs and across the plane of said second named ribs, and integral abutments on the door adapted to present bearings for said latching means.

7. A railway car door adapted to be pivotally mounted adjacent one end and provided with movable latching means adjacent the opposite end, said latching means extending substantially parallel with the hinge axis of the door, said door on its outer side being formed with integral rigidifying ribs extending contiguously with the latching means and disposed on opposite sides of the path of travel thereof, and other integral ribs extending between and connecting said first named ribs.

8. A railway car door adapted to be pivotally mounted adjacent one end and provided adjacent its opposite end with movable latching means carried by the door and movable therewith, integral reinforcing means formed on the door and extending contiguously with said latching means; means for controlling movement of the latching means relatively to the reinforcing means, said means including a link pivotally connected with the latching means and to the door, and integral bracket means outstanding from said rib means on the door for receiving one end of the link.

9. In a car having a discharge opening and a pivoted door, the combination of bracket members mounted on fixed portions of the car at the side edges of the door, a latching element mounted for bodily and rotatable movement on the door and having portions extended beyond the sides of the door for co-operable engagement with the brackets, integral means outstanding from the main body of the door adapted to form seating means for the latching element, and a link connection between the latching element and the door, said link being pivotally mounted on an integral portion of the door.

10. In a railway car door of the cast metal type having integral reinforcing sections outstanding from the door on the under side thereof, a door latching element movably associated with said integral reinforcing means, means for controlling movement of the latching element including a link pivotally connected to the latching element and to the door, said door having integral lug means for receiving one end of the link.

In witness that I claim the foregoing I have hereunto subscribed my name this 16th day of August, 1930.

GEORGE B. DOREY.
